UNITED STATES PATENT OFFICE.

JOHN SIDNEY WILLIAMS, OF BRISBANE, QUEENSLAND, AUSTRALIA.

ADJUSTABLE FASTENER FOR HINGED STRUCTURES.

Application filed June 22, 1926, Serial No. 117,702, and in Australia September 21, 1925.

My invention relates to fasteners adapted to adjust and lock hinged structures, including casement windows and pivoted fanlights, all of which are called herein windows or sashes for brevity. The window will thus be held closed, or in a selected partly, or in a fully, open, position, as may be required from time to time. One feature of my invention is that, instead of all the window 10 hinges being independent of my device, one of the said hinges forms a hinge of my fittings, thus simplifying construction and facilitating correct relative positioning of the various parts. Supplementary to the 15 said hinge, the window will have any other suitable hinge or hinges, not forming part of this invention.

My fittings include two principal members to be set in a suitable plane—either vertical 20 or horizontal. One of these members will be fixed to the stationary frame around the window, and the other member will be fixed to the window sash and will swing with it. The latter member carries a spring urged 25 pawl which will engage the other, herein called the fixed member.

Constructions embodying this invention are applicable to windows hinged along one side, and also to windows hinged on opposite sides.

In the drawings herewith Figure 1 is a plan of horizontally set fittings, for a window hinged at one side only; the fittings are shown in partly open position, a part of 35 the swinging plate being broken out to show clearly the rail of the fixed plate below it.

Figure 2 is a front elevation of the swinging plate of Figure 1. This plate is to be fixed to the window sash; in this view a part 40 is shown in section through a socket for the pawl pivot pin, and the recess for the pawl spring is also shown.

Figure 3 is a front elevation of the fixed plate of Figure 1,—to be fixed to the fixed 45 frame of the window, that is the framing external of the sash.

Figure 4 is a perspective view of the pawl, but in reverse position relatively to Figure 1, and with a part broken away.

Figure 5 shows modified fittings to be set 50 in a vertical plane for use on a window hinged at opposite sides, and which may be in a high location and operated by a cord or the like from below.

55 The window or sash will be located at W, and its fixed frame at F.

1 is a stationary plate hinged to a swinging plate 2 by a pin 3, on one of the plates, projecting through a hole 4 in the other plate. In Figure 1 the hinge pin projects 60 from an offset 1^a of plate 1 and engages a hole 4 in an offset 2^a of plate 2.

To facilitate the attaching of plate 1 to frame F and the attaching of plate 2 to the window the plates have parts 1^b, 2^b having 65 holes 1^c, and 2^c respectively. The offsets 1^a, 2^a have each a hole 1^d, 2^d respectively all holes being to receive wood screws.

The plates are made of skeleton form to 70 secure various advantages.

The swinging plate has an outer curved rail 7 which is adjacent to an outer curved rail 8 of the fixed plate, each curve being suitable when it has the hinge pin 3 as a 75 centre, as this allows the under rail to support a relatively considerable length of the upper rail as best indicated by Figure 1.

Rail 7 is formed with a lug 9 which projects beyond the edge of rail 8 and carries a pawl 10, having a tooth 10^a which faces the outer edge of rail 8, that edge being notched at 11, 11^a, and 11^b, any suitable number of notches 11^a being provided between notches 11 and 11^b.

Lug 9 has a boss 9^a having a hole 12 in 85 register with a hole 12^a in the pawl. These holes receive a pivot pin 13. Each hole is enlarged on the meeting faces 12^b, 12^c, respectively, to receive a pawl spring 14 of wire for example. The middle part of the 90 wire is suitably positioned as coiled around the pin 13, the ends of the spring being anchored in slot recesses 12^d, 12^e respectively. The pawl tooth, 10^a, normally engages one of the aforesaid notches under the pressure 95 of the spring. Recesses 12^d, 12^e are in the lug 9 and pawl 10 respectively.

By using notch 11 the pawl tooth locks the window in closed position; by using notch 11^b it holds the window widely open, although as herein explained some further opening is possible in the case illustrated; and by using any intermediate notch 11^a the window position can be otherwise adjusted.

To facilitate window adjustment I provide 105 a pair of finger lugs, of which one lug, 15, is on the swinging rail 7, and the other lug 15^a forms the pawl head. These lugs are normally, under the influence of spring 14, somewhat separated when not being operated, but they can be brought together by pressure between a finger and thumb—and to 110

facilitate such pressure these lugs project clear of rail 7. The said spring forces the tooth 10^a toward rail 8 into any notch which is opposite to it. But the said finger pressure lifts tooth 10^a clear; then the operator while still pressing both lugs together, moves them in the appropriate direction, until a suitable notch is reached. He then releases the lugs and the tooth will enter the desired notch. I make the maximum distance between the finger lugs slight without unduly limiting the rise of the tooth.

There is on the stationary plate a stop 16 in the path of a projection 16^a on the swinging plate. The projection is on the pawl in Figures 1 and 4 but can be in any convenient position it being shown on plate 2 in Figure 5, adapted to be stopped by surface 16^c of rail 8. The stop allows the pawl tooth to pass all the notches but prevents excessive opening of the window.

The projection 16^a in Figure 1 by projecting transversely of notched rail 8 prevents rail 7 shifting up from the notched rail 8. It is obvious that gravity would be utilized as to window motion in some cases—see Figure 5 but I do not claim novelty as to such use, nor do I claim the use of depending cords as 17, 17^a, attached to lugs 15, 15^b and extending within hand reach, so that when the window is closed the user can open it by means of the cord.

If the window begins to close by gravity when, thereupon, the cord is released, such closing would become automatically arrested as soon as the tooth came to a notch in its

path. Pulling cord 17^a would swing pawl 10, and lift tooth 10^a, and would open the window by swinging plate 2, until if desired, projection 16^a met stop 16^c. Cord 17 is not essential but is convenient as it allows a user to stop or to steady window movement. Normally during the opening the tooth 10^a is allowed to enter a notch and thus fix the window. When partly closing the window the pawl tooth is allowed to enter any selected notch.

In my claim the word frame means the stationary frame which carries the sash.

I claim:—

• A window fastener of the character described, the combination of a fixture attachable to the window frame comprising a notched quadrant projecting outwardly and provided with an upright pivot post disposed at the center of the segment a plate carried by the window and pivoted on said post, said plate having an arm carrying a pivot pin and a notch to move into register with the notches of the sector, a spring actuated dog mounted on the last named pivot pin and having one end urged in the direction of the notches of the quadrant, and a cord at the other end of the dog and loose in the arm of the said plate whereby the operation of pulling on the cord will first release the dog from the quadrant and then swing the window into open position.

In witness whereof I have hereunto set my hand.

JOHN S. WILLIAMS.
